UNITED STATES PATENT OFFICE.

VERNON BROWN AND JOSEPH H. PENGILLY, OF LOS ANGELES, CALIFORNIA.

RELAY.

Application filed July 12, 1920. Serial No. 395,612.

To all whom it may concern:

Be it known that we, VERNON BROWN and JOSEPH H. PENGILLY, both citizens of the United States, residing at Los Angeles, 5 county of Los Angeles, and State of California, have invented a new and useful Improvement Comprising the Relay described in the following specification.

Our invention relates to relays which are 10 commonly connected into an electric circuit for the purpose of accomplishing certain results upon the occurrence of predetermined conditions within that circuit. It more particularly relates to what is known as the 15 overload relay, these relays being inserted in a circuit to accomplish certain results upon the occurrence of overload or excessive current conditions in that circuit.

The particular embodiment of overload 20 relay shown and described is one which is adapted to be used in connection with the no voltage coil of a circuit breaker. Circuit breakers provided with no voltage coils are common in the art, the no-voltage coil being 25 connected to the circuit to be protected and being mechanically so arranged that the circuit breaker opens whenever the voltage falls.

Our invention comprises a relay which is 30 adapted to open the circuit to the no voltage coil in the event that excessive current is imposed upon this circuit to be protected, the no-voltage coil opening the circuit breaker as soon as its circuit is interrupted.

35 Our invention further comprises a relay which is so arranged that the opening of the circuit of the no voltage coil does not occur until the overload condition has persisted for a certain length of time, the exact interval depending upon the severity of the 40 overload and the adjustment of the relay.

A further object of the invention is to provide a relay which can be adjusted for various overload conditions and which will 45 be also so constructed that it can be readily inspected, repaired and adjusted.

Further objects and advantages will be made evident hereinafter.

50 Referring to the drawings which are for illustration only,

Fig. 1 is an elevation partly in section of our invention and Fig. 2 is a plan view in section on a plane represented by the line 2-2 of Fig. 1.

55 The embodiment of the invention shown

is provided with two overload coils 12 carried in a magnetic circuit 13. Insulating tubes 14 project up inside the magnetic circuit 13 and inside the coils 12, an armature or plunger 15 being provided in each of the 60 tubes 14. The tubes 14 are provided with enlarged heads 16 and with an annular groove 17 on their lower edge. Dash pots 18 also formed of insulating material fit into the groove 17 being held tightly in place by 65 means of a lower bar 19, which is forced upwardly by a thumb nut 100 on a screw 20 forcing the dash pots 18 against the heads 16 and forcing the heads 16 against an upper bar 21 which is held by means of a set screw 70 22 on the screw 20. The screw 20 is calibrated as shown at 23 being secured by means of a screw 24 in the lower cross bar of the supporting frame 13. Extending 75 across the bottom of each of the dash pots 18 is a partition 30 dividing the lower portion of the dash pot into two spaces in which are placed pools of mercury. Metal members 32 secured in the head 16 project into these pools and are connected by means of wires 80 33 and 34 with each other or with an external circuit which will hereinafter be described.

Secured to the armatures 15 by rods 40 are 85 pistons 41, these pistons fitting fairly tight in the dash pots 18 and having perforations through which the rods 32 pass. Fitting loosely in the pistons 41 are bridging members 50, these bridging members being formed of metal and of the shape shown in 90 Fig. 1. Two bridging members 50 are provided in each of the dash pots 18, these members normally resting on the bottom of the dash pot and connecting the pools of mercury 31 together.

95 The method of operation is as follows:

The coils 12 are connected into the circuit to be protected. This may be a single phase circuit in which case one of these coils may be connected into either wire of 100 that circuit or it may be a three phase circuit in which the coils 12 are each connected into one phase of that circuit. The wires 33 are connected in series with the circuit and with the no voltage coil on the 105 circuit breaker, this coil not being shown as the circuit breaker forms no part of the present invention. The circuit is then completed to the no voltage coil through one of the wires 33, its metal rod 32, the bridg- 110

ing members 50 connecting the pools of mercury 31, the wire 34 connecting two of the dash pots in series with each other. Upon the occurrence of an overload in the 5 circuit one or both of the armatures 15 is pulled upwardly. The space above the pool of mercury is filled with an insulating liquid preferably a mineral oil. Immediately upon the establishment of a pull on one of the 10 pistons 41 through the rod 40 from the armature 15 a partial vacuum is formed below the piston 41, the pressure of the air upon the top of this piston resisting the pull of the armature 15. This partial vacuum is slowly relieved by the flow of oil around the periphery and through the holes in the piston 41 so that the piston moves upward slowly under the influence of this pull. During the early part of this movement, the bridging members 50 remain stationary sliding free in the piston 41 until this piston reaches a certain position which is determined by the shape of the bridging 15 members 50. When the piston reaches this position it starts to lift the members 50 gradually raising them out of the pools of mercury and opening the circuit between the wires 33 and 34. As soon as this circuit 20 is opened, the no voltage coil of the breaker operates and opens the circuit breaker thus disconnecting the circuit to be protected from the source of power. This de-energizes the coils 12 and the armatures 15 fall under the influence of gravity re-establishing the 25 circuit so that when the circuit breaker is again thrown in, the no-voltage coil will be energized. If it is desired to change the calibration so that the armatures 15 operate upon a higher or lower current, the set 30 screw 22 is released and the dash pots 18 together with the bars 19 and 21 are moved up and down by turning the thumb nut 100 on the screw 20, thus moving the whole assembly up or down on the screw 20. When 35 the proper calibration is reached the set screw 20 is forced into place. It is then possible to remove the thumb nut 100 and the bar 19 and to take off the dash pots 18 for inspection, cleaning or refilling. The 40 dash pots can then be replaced without disturbing the calibration in any way.

Our invention has a peculiar utility in connection with induction motors. These motors are commonly provided with a no-voltage release circuit breaker and our invention is designed to protect such motors against excessive current. Such motors, however, require comparatively heavy currents to start. These starting currents being 45 of brief duration, it is possible by the use of our device to protect against continued overloads and at the same time to allow the motor to draw a heavy current during the starting period without tripping the circuit breaker.

We claim as our invention:

1. A contact making device comprising: a head; a dash pot removably secured to said head; electrically conducting liquid in the lower end of said dash pot; an insulating 70 partition dividing said body of liquid into two pools insulated from each other; two conducting members each secured in said head, one of said members making electrical contact with one of said pools, and the other 75 of said members making electrical contact with the other of said pools; a conducting bridging member normally having one end making electrical contact with one of said pools, the other end simultaneously making 80 electrical contact with the other of said pools; and means for moving said bridging member upwardly to break contact with said pools.

2. A contact making device comprising: a head; a dash pot removably secured to said head; electrically conducting liquid in the lower end of said dash pot; an insulating 85 partition dividing said body of liquid into two pools insulated from each other; two conducting members each secured in said head, one of said members making electrical contact with one of said pools, and the other 90 of said members making electrical contact with the other of said pools; a conducting bridging member normally having one end making electrical contact with one of said pools, the other end simultaneously making 95 electrical contact with the other of said pools; a piston sliding in said dash pot, said conducting members projecting through said piston; and means by which said piston moves said bridging member upwardly to break contact with said pools.

3. A contact making device comprising: a head; a dash pot removably secured to said head; electrically conducting liquid in the lower end of said dash pot; an insulating 100 partition dividing said body of liquid into two pools insulated from each other; two conducting members each secured in said head, one of said members making electrical contact with one of said pools, and the other 105 of said members making electrical contact with the other of said pools; a conducting bridging member normally having one end making electrical contact with one of said pools, the other end simultaneously making 110 electrical contact with the other of said pools; a piston sliding in said dash pot, said conducting members projecting through said piston, said bridging member being carried by said piston; and means for moving 115 said bridging member upwardly to break contact with said pools.

In testimony whereof, we have hereunto set our hands at Los Angeles, California, this 1st day of June, 1920.

VERNON BROWN.
JOSEPH H. PENGILLY.
